CLAIM

The ornamental design for a female hose coupling, as shown and described.

DESCRIPTION

FIG. 1 is a right front perspective view of a female hose coupling;

FIG. 2 is a side elevation view of a female hose coupling, all sides being identical to that shown;

FIG. 3 is a top plan view of a female hose coupling; and, FIG. 4 is a bottom plan view of a female hose coupling. The broken line showing is included for the purpose of illustrating environment and forms no part of the claimed design. The female hose coupling design includes a twelve faceted surface and a circumferentially disposed channel. The number of facets shown in the drawings is for illustrative purposes only. The number of facets may vary between eight and fourteen.

1 Claim, 2 Drawing Sheets
